UNITED STATES PATENT OFFICE.

ABEL C. BRIGGS, OF WILMINGTON, OHIO.

ROADWAY CONSTRUCTION.

1,286,925.

Specification of Letters Patent. Patented Dec. 10, 1918.

Application filed February 16, 1918. Serial No. 217,467.

To all whom it may concern:

Be it known that I, ABEL C. BRIGGS, a citizen of the United States, residing at Wilmington, in the county of Clinton and State of Ohio, have invented certain new and useful Improvements in Roadway Constructions, of which the following is a specification.

This invention relates to road ways and has particular reference to road way construction and the method of producing road ways.

The objects of my invention are to provide a road way of superior construction so arranged as to offer a high resistance to wear; to so construct my improved road way as to admit of its being produced at a comparatively low cost and at the same time obviate the necessity of frequent expensive repairs and to otherwise provide a durable and economical road construction.

With these and other objects in view as will appear as the description proceeds, the invention accordingly consists in the novel method and features of construction which are set forth with particularity in the appended claims.

In the accompanying drawing,

Figure 1 is a plan view of a portion of a road way having my improved construction.

Fig. 2 is a transverse section of the road way.

Similar numerals refer to similar parts throughout the several views.

It has been demonstrated that a concrete road surface is greatly to be desired on account of its smoothness and wearing qualities but where such a construction is provided for the entire width of the road it has been found to so greatly increase the expense of road building as to make its use almost prohibitive except possibly in certain localities. My improved construction comprises a combination of concrete road sections with the usual or ordinary macadam sections and in carrying out my plan of construction I build or otherwise provide, on opposite sides of the longitudinal center of the road two parallel strips or sections of concrete. These sections or strips form track ways or bearing surfaces for the opposing wheels of vehicles. Each of these concrete strips which are shown at 1 in the drawing is comparatively narrow and assuming that such strips are in the neighbor-

hood of two or three feet in width and that a substantially equal space exists between the strips it will be understood that said strips will cover only a comparatively small proportion of the entire road way. In producing the track strips 1 any usual concrete construction may be employed, such as a base of gravel, broken stone and sand united by cement or otherwise, and the usual top layer of cement and sand mixed in the proper proportions. I do not, however, desire to confine myself to the exact concrete mixture but intend that the word concrete as used herein shall cover what is generally understood by the term when applied to paving.

The space between the two strips 1 which is indicated at 2 is filled or built up of what is known as macadam and preferably of what is commonly called water bound macadam until the filling is flush with the top of the concrete surface. The sections 1 are provided at desirable intervals with transverse expansion joints such as are indicated at 3 in Fig. 1 and said concrete sections are reinforced and anchored against lateral or individual movement by providing at desirable intervals transverse reinforcing bars or rods 4 which are embedded within said concrete members and pass through the center macadam strip 2. In order to further reinforce the concrete sections I provide a plurality of reinforcing rods or bars 4^A which extend longitudinally through the concrete sections.

The outer side of each of the strips 1 is as shown at 5 beveled outwardly and downwardly and adjoining each of these beveled sides is the inner correspondingly beveled side of an outer macadam section 6 which is slightly inclined from the upper surface of the adjacent concrete section to the outer extremity of the road way. These sections 6 are embedded in longitudinally extending kerfs formed in the base of the road way, and said kerfs by reason of the outer upstanding walls thereof serve to prevent lateral separating movement on part of the strips 1 and the filling layers 2 and 6.

In constructing a new road way of the character herein shown and described it will be understood that the road base is first brought down to the proper depth or level after which the concrete strips 1 are built up between the usual mold boards in the ordinary manner. The mold boards being

removed the center section 2 and the outer side sections 6 are then constructed. It will be understood of course that the reinforcing rods 4 and 4^A are inserted in the concrete 5 during the process of building the same.

From the construction and method of production which I have described herein it will be understood that the two strips 1 may serve as the bearing surfaces for the wheels 10 of a vehicle thus admitting of the automobile or other vehicle traveling wholly upon the concrete strips excepting during the passing of another vehicle. By the construction described it will further be understood that an 15 exceedingly durable road way is provided at a comparatively small cost inasmuch as the more expensive bearing surfaces 1 compose a part of the road way only and yet are so arranged as to take up the greater portion 20 of the wear. By using the road in the manner described it is obvious that the life of such a road way will be greatly increased owing to the fact that the center and outer side sections are constructed of a material 25 which is ordinarily more sensitive to the wearing action of tires and these sections will have comparatively little use as the natural tendency of a driver will be, except when passing another vehicle, to use the 30 hard and comparatively smooth surface of the sections 1.

It has been found that the greater the area of a concrete surface the greater the tendency of the concrete layers to crack or 35 separate and it will be observed that by my construction the concrete members are comparatively narrow which must greatly lessen the liability to cracking.

Having described my invention what is 40 claimed as new is:

1. A road way comprising a base having a pair of spaced longitudinally extending kerfs formed therein, said kerfs being formed to comprise inclined bottom surfaces 45 and up-standing side walls, spaced parallel strips of concrete situated upon said base and located between said kerfs, said strips including inclined outer edges and vertically disposed inner edges, a layer of filling 50 material interposed between the vertical edges of said strips and having its upper surface formed to terminate evenly with the corresponding surfaces of said strips, and outer layers of filling material situated 55 between the inclined edges of said strips and the up-standing walls of said kerfs, the upper surfaces of said outer layers being inclined to extend substantially parallel with the bottom surfaces of the kerfs.

2. A road bed comprising a base, having a 60 pair of spaced longitudinally extending kerfs formed therein, said kerfs being formed to comprise inclined bottom surfaces and up-standing side walls, spaced parallel strips of concrete situated upon said 65 base and located between said kerfs, said strips including inclined outer edges and vertically disposed inner edges, a layer of filling material interposed between the vertical edges of said strips and having its upper 70 surface formed to terminate evenly with the corresponding surfaces of said strips, outer layers of filling material situated between the inclined edges of said strips and the up-standing walls of said kerfs, the upper 75 surface of said outer layers being inclined to extend substantially parallel with the bottom surfaces of said kerfs and longitudinally and transversely extending reinforcing and anchoring members passing 80 through said strips.

3. A road way comprising a base, spaced parallel strips of concrete situated upon said base, said strips including inclined outer edges and substantially vertical side edges, 85 a layer of filling material interposed between the vertical edges of said strips and having its upper surface formed to terminate substantially evenly with the corresponding surfaces of said strips, outer layers of filling 90 material situated to engage the inclined outer edges of said strips, the upper surfaces of said outer layers being inclined outwardly and downwardly, and means tending to prevent lateral spreading movement on part of 95 said outer layers.

4. A road way comprising a plurality of spaced parallel strips formed from longitudinally aligned monolithic sections, reinforcing means connecting said strips in both 100 longitudinal and transverse directions, an inner layer of filling material situated between said strips and serving to maintain the layer in properly spaced positions, said layer having its upper surface disposed on 105 substantially the same plane as the corresponding upper surfaces of said strips, inclined outer layers of filling material cooperative with said strips, and means serving to prevent lateral separation of said 110 outer layers with respect to said strips.

In testimony whereof I affix my signature in presence of two witnesses.

ABEL C. BRIGGS.
